(57) **CLAIM**

The ornamental design for a multi functional carry-on phone charging cord, as shown and described.

DESCRIPTION

FIG. 1 is a front and top perspective view of a multi functional carry-on phone charging cord design showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof.

FIG. 9 is another perspective view thereof, showing the charging heads are hidden; and,

FIG. 10 is an enlarged view of the multi functional carry-on phone charging cord, taken from the circle part in FIG. 1. The dash-dash lines in FIGS. 1 and 10 represents the bounds of the enlargement taken from FIG. 1 and forms no part of the claimed design.
